DESIGN.

H. E. HYMER.

DISH.

APPLICATION FILED APR. 24, 1918.

52,275.

Patented Aug. 20, 1918.

Harry Eugene Hymer Inventor
By his Attorney
Clarence G. Campbell

UNITED STATES PATENT OFFICE.

HARRY EUGENE HYMER, OF MAMARONECK, NEW YORK, ASSIGNOR TO MADDOCK & MILLER, OF NEW YORK, N. Y., A CORPORATION OF NEW YORK.

DESIGN FOR A DISH.

52,275.

Specification for Design.

Patented Aug. 20, 1918.

Application filed April 24, 1918. Serial No. 230,589. Term of patent 3½ years.

To all whom it may concern:

Be it known that I, HARRY EUGENE HYMER, a citizen of the United States, residing at Mamaroneck, county of Westchester, and State of New York, have invented a new, original, and ornamental Design for Dishes, of which the following is a specification, reference being had to the accompanying drawing, forming part thereof.

The figure is a plan view of a dish, showing my new design.

I claim:

The ornamental design for a dish as shown.

HARRY EUGENE HYMER.
